UNITED STATES PATENT OFFICE.

EDWARD ERICKSON, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOEMAKING-MACHINE.

1,137,125.

Specification of Letters Patent. Patented Apr. 27, 1915.

Application filed March 21, 1912. Serial No. 685,176.

To all whom it may concern:

Be it known that I, EDWARD ERICKSON, a citizen of the United States, residing at Beverly, in the county of Essex and State 5 of Massachusetts, have invented certain Improvements in Shoemaking-Machines, of which the following description, in connection with the accompanying drawings, is a specification, like reference characters on 10 the drawings indicating like parts in the several figures.

This invention relates to shoe making machines and is herein shown and described as embodied in a machine for breasting 15 heels, although it is to be understood that the invention in its broader aspects is applicable to other uses.

It is the usual practice in this country to 20 secure heels to shoes in a rough state and then to trim the convexly curved portions of the heel upon a trimming machine, leaving the rough forward portion to be removed by an operation known as "breasting," by which the straight or concave front 25 face, or so-called "breast," of the heel is shaped. It is usual to perform this operation by means of a flat or a gouge-shaped knife between which and the jacked shoe there is relative reciprocatory movement in 30 a direction substantially perpendicular to the tread face of the heel, a stop being provided to arrest the cutting action of the knife at the lower edge of the heel and thus avoid injury to the shank portion of the sole 35 by excessive movement of the knife. In this method of breasting heels the knife is driven directly across the fibers of the leather in the heel and considerable force is necessary to effect the cut. This force is 40 sometimes so great that the portion of the heel below the knife is somewhat compressed before the fibers will yield to the cutting edge of the knife and then when finally the knife begins to cut the reaction 45 of the compressed portion is apt to cause the knife to cut more deeply than is desired. Frequently also the inner face of the insole does not fit closely against the upper face 50 of the last in the shoe and the excessive pressure of the knife against the heel tends to flatten the sole against the last and when the knife has passed through the heel and the pressure of the knife against the sole is relaxed, the sole, by tending to resume its

normal shape, may react against the knife 55 and cause it to injure the shank portion of the sole.

It is an object of the present invention to provide novel knife actuating mechanism for effecting the breasting operation with a 60 minimum of resistance thereto by the work and for producing a breast face which will be so smooth as to require little or no further finishing. With these objects in view the knife, as an important feature of 65 the invention, is mounted so that it may rock, swing or oscillate about a point lying substantially in the plane of the knife or about an axis perpendicular to the plane of the knife. Preferably this point or axis is 70 in, or adjacent to, the cutting edge of the knife but it may, without departing from the invention, be located below or above the cutting edge and within the body of the knife or outside of it. Preferably and as 75 herein shown the knife carrier is supported by a plurality of links and means is provided for giving the carrier a rocking movement upon the links laterally of the shoe, the movement of the knife carrier being preferably in the plane of the knife or parallel thereto.

It is also a feature of the invention that the links supporting the knife carrier are inclined to each other so that their longitudinal axes, if extended, would intersect. Preferably this point of intersection is located approximately at the center of the cutting edge of the knife. When so arranged the rocking movement of the knife 85 carrier upon the links in the plane of the knife will cause the knife to rock or oscillate about the said point of intersection and consequently the portions of the knife edge to each side of that point will be given a 90 substantially vertical movement or a movement perpendicular to the tread face of the shoe shank. The movement given the knife is preferably only slight, but very rapid, so that all portions of the cutting edge except 100 the center will vibrate rapidly in a plane perpendicular to the tread face of the shank.

The vibrating movements of the knife being but slight, it is practicable to employ knives of any convenient radius of curvature upon heels of any ordinary height without danger of the vibratory movements of the knife interfering with the relative move- 105

ment of the knife and shoe necessary to effect the breasting operation. Preferably and as shown the knife remains stationary except for its vibratory movement and the shoe is raised toward the knife by foot power. The effort, however, necessary for effecting the operation is very slight as the vibratory movements of the knife cause it to effect its actual cutting by the power applied thereto, the movement of the shoe to the knife being merely a feeding movement requiring little effort upon the part of the operator.

As an important feature of the invention the location of the center about which the knife is oscillated or vibrated is not fixed but may be adjusted. To accomplish this the links by which the knife carrier is supported are so arranged that the degree of their inclination to each other may be varied and as herein shown the supports of the upper ends of the links are mounted for movement toward and from each other and preferably this movement in each case is about the opposite end of the link as a center, so that the inclination of the links may be varied without changing the vertical position of the knife carrier. It is a convenient feature of the invention that the upper ends of the links may be simultaneously moved equally. Specifically the upper end of each link is mounted in a block which is, in turn, mounted for movement in a curved slot struck from the lower end of the link as a center and the blocks are connected by a right and left screw which is held from longitudinal movement. Adjustment of the center of oscillation above or below the edge of the knife results in giving the edge portion of the knife a slight lateral movement lengthwise of the edge while the side portions retain their vertical vibratory movements. This results in a draw cut at the center of the knife and a draw cut combined with a chopping cut at the side portions thereof.

It is also within the invention to give the knife carrier a somewhat greater vibratory movement than is necessary for the ordinary breasting operation, this being particularly feasible when a flat knife is used. With this extra movement a knife with an edge having a given vertical curvature will breast a shank of materially greater curvature and further, since the limiting position of the movements of the knife edge is not a circular curve but one having a greater degree of curvature at its middle portion, the machine when the vibratory movements of the knife are increased is particularly adapted for breasting shanks having a longitudinal ridge instead of an approximately cylindrical surface.

As a further feature of the invention there is provided, in combination with the vibrat-

ing knife, a presser tread plate which is normally resiliently depressed and against which the shoe is brought in its upward movement by the treadle mechanism. The tread plate is provided with a tread contacting portion which may be adjusted to coincide with the rear face of the knife so as to serve as a gage for guiding or positioning the heel relatively to the knife while it is being raised toward the knife and before actual contact therewith takes place.

The provision of a resilient depressed heel tread face engaging member against which the shoe is pressed in its upward movement toward the knife not only enables the shoe to be properly positioned prior to the engagement of the shoe with the knife, as described, but serves to hold the shoe against lateral displacement during the cutting action of the knife. The spring which depresses the tread plate is only slightly tensioned when the work first engages the tread plate so that the shoe may be readily positioned during the first portion of its vertical movement and as the shoe is raised farther, the tension of the spring is increased so that the shoe is securely clamped when it reaches the knife and remains so until after the breasting operation when it is lowered and released.

These and other features of the invention will appear more fully from the following detailed description in connection with the accompanying drawings, in which,—

Figure 1 is a rear elevation of a machine embodying the invention; Fig. 2 is a side view of the machine; Fig. 3 is a sectional detail taken transversely of a shoe being treated and in front of the knife which is in the act of breasting the heel; Fig. 4 is a perspective view of parts of the machine head showing the manner of mounting the knife carrier for vibratory movement; Fig. 5 is a detail of the mechanism for adjusting the inclination of the links which support the knife carrier.

The column or frame of the machine is designated by the numeral 2. A jack for supporting the shoe in operative relation to the breasting mechanism is provided at the side of the frame and comprises a casting 4 pivoted by a stub shaft 6 to the machine frame. The casting 4 carries bearings 7, 9, in which a jack post 10 is mounted for longitudinal movement. The lower portion of the post 10 where it passes through the bearing 9 is squared while the upper portion is cylindrical. At the point of juncture between the square and cylindrical portions a shoulder is formed which may rest upon the bearing 9 to limit the downward movement of the post 10. Below the post 10 is a vertical sliding member 12 mounted in bearings 14, 16 and jointed to a treadle 20 which is pivoted to the frame at 22 so that operation

of the treadle slides the member 12 vertically.

The jack post 10 projects below the lower end of the bearing 9 and rests in a recess 13 in the top of the member 12. The post 10 carrying the shoe and jack may then be swung, in a direction which coincides with the length of the shoe, about the pivot 6 to permit the shoe to be readily placed upon and removed from the jack and to position the shoe properly relatively to the knife, the extent of this swinging movement being limited by the end walls of the recess 13.

Fixed to the upper end of the post 10 is a U-shaped bracket 30 through the upper arm of which a threaded post 32 slides. Between the arms of the U-shaped bracket is a hand wheel 34 which is threaded upon the post 32 and by rotation of which the post 32 may be adjusted vertically. The periphery of the wheel 34 is toothed or roughened and a spring pressed detent 36 is provided upon the bracket to engage the toothed portion of the wheel and prevent accidental rotation thereof. Means, comprising an arm 40 fixed to the post 32 and a pin 42 on the bracket 30 engaging a hole in the arm 40, are provided for preventing rotation of the post 32 and permitting vertical movement thereof.

The post 32 is shown as carrying the usual metal work plate for breasting heels "off the last" but it is to be understood that the post 32 may be provided with a heel pin, and might carry a toe rest, for use in breast-
35 ing shoes "on the last," if desired.

Mechanism for clamping the shoe in position to be operated upon is provided which acts automatically as the shoe is raised. This mechanism comprises a tread presser 50 which is carried by a slide 52 mounted for vertical movement in the guides 54 on the head of the machine. The tread presser 50 is pivoted to the slide by a pintle 56 about which it may be adjusted by the screw 58 to 40 change its inclination in accordance with the angle it is desired to have between the tread face and breast of the heel. The heel contacting portion of the tread presser 50 comprises a slide 60 which may be adjusted to 45 ward and from the knife by loosening the screw 62. This slide is adjusted against the rear face of the knife so that its front edge coincides substantially with the cutting edge of the knife and serves as a gage for setting 50 the heel relatively to the knife before it comes in contact therewith. The slide 52 carrying the tread plate engages one end of a lever 70 which is pivoted between its ends at 72 to the machine frame and has the other 55 end pivoted to a rod 74 which extends loosely through a lug 76 on the machine frame. The rod carries adjustably a collar 78 and on the rod 74 between the collar 78 and the lug 76 is an expansion spring 80 which tends to hold the tread presser down

as far as is permitted by nuts 82 on the rod 74 which contact with the lug 76 and form adjustable limiting means for the downward movement of the presser 50.

The knife mechanism comprises a knife carrier 90, Fig. 4, to which the knife 88 is clamped by screws 91, and which carries adjustable abutments for the top end of the knife in the form of screws 92. The knife carrier 90 is mounted for movement substantially in the plane of the knife by means of links 94, which have rounded ends engaging cylindrical sockets formed respectively in the carrier 90 and in blocks 96 mounted in the head of the machine. The links 94 are inclined to the vertical at an angle normally approximating 30°. It will therefore be seen that if the knife carrier 90 is rocked on the links 94, Fig. 1, one link will have its inclination increased and the other have its 85 inclination lessened and vice versa when the holder moves in the opposite direction. In other words, the slight movements of the carrier will be in effect movements substantially about a fixed point which lies at the 90 intersection of the longitudinal axes (extended) of the links 94. This point is preferably, and as shown, at the edge of the knife, but means is provided for adjusting the position of the point vertically so that it 95 may be maintained at the edge of the knife as the knife is ground away or so that a slight lateral movement of the knife coincidentally with the vibratory movements thereof may be secured by adjusting the center of 100 oscillation above or below the edge of the knife. For this purpose the blocks 96 which carry the upper ends of the links 94 are mounted in the head of the machine in grooves 97 which are curved from the lower 105 ends of the links 94 as centers and said blocks 96 are connected together by a right and left screw 99 which is threaded through blocks 101 pivotally secured to the blocks 96. Longitudinal movement of the screw 99 is 110 prevented by a collar 103 fixed to the screw and engaging a suitable slot in the machine head.

Obviously by turning the milled head of the screw 99 the inclination of the links 94 may be changed equally and oppositely relatively to a line extending longitudinally of the knife 88 and the point of intersection of the links adjusted above or below the edge 115 of the knife or maintained at the edge of the knife as it is ground away in use. It will be seen, further, that the adjustment of this point, center, or axis of oscillation above or below the edge of the knife will produce a slight lateral movement of the knife as a 120 whole as well as equal and opposite vertical movements of the outer edges of the knife to which latter movements the knife is practically limited when the axis is located at 125 the edge of the knife. The effect on the 130

knife of rocking the carrier is to force down one end of its cutting edge and to raise the other end and vice versa about a substantially stationary point lying in its edge midway of the length thereof. The upper portion of the knife carrier is formed with a ball socket to receive a ball 100 which is secured to a connecting rod 102 and is held in its socket by a retainer 104. The opposite 10 end of the rod 102 is similarly connected, but eccentrically, to a hub 106 which is mounted on a shaft 110 in the head of the machine. The shaft 110 is driven from a pulley 112, a loose pulley 114 and a belt shifter 116 being also provided. The ball socket in the knife carrier is in alinement vertically with the axis of the shaft 110, Fig. 1, but is displaced horizontally, Fig. 2, to an extent equal to the eccentricity of the 20 socket in the hub 106. By this construction it will be clear that the rod 102 will be perpendicular to the face of the hub at one point in the rotation of the hub and that at this point the knife carrier will be pushed 25 to its fullest extent to the right, Fig. 1. When the hub is rotated 180° from this position, the rod will have reached its greatest possible inclination and the carrier will be in its position of greatest movement to the 30 left. The shaft 110 is rotated very rapidly and the knife is thereby given an oscillatory vibration which enables it to cut through the work speedily and with ease and accuracy. Fig. 3 shows in full lines one position of 35 the knife in its vibratory movement and in dotted lines its opposite position.

It is obvious that the movement takes place about a point *a* which is practically stationary, and that the other portions of 40 the edge of the knife have a slight vibratory movement in a substantially vertical direction. The lateral movements of the upper portions of the knife are so slight that they do not interfere with the use of a gouge 45 knife of a high degree of curvature or with the breasting of high heels. The edge of the knife is given the usual curvature to fit the crowning of the shank and the vertical movements of the side portions, while they 50 tend to increase the effective curvature of the knife edge, are so slight in extent that the result is rather to effect the complete detachment of the chip at the sides without cutting the shank than to necessitate the use 55 of a knife of less curvature than the given shank.

A shank stop 120 has a toothed upper portion, Fig. 5, which is engaged by a worm 121 mounted in the machine head by rotation of which the stop may be adjusted vertically and a screw 122 may be provided for 60 more securely holding the stop in adjusted position with its contacting end in the plane of the knife edge so as to arrest the shoe 65 before the shank is cut. In operation, the

jack being in its lowered and outwardly swung position, a shoe is placed upon it and swung under the knife with its heel under the tread presser 50. The shoe is then raised by pressure upon the treadle until the heel 70 contacts with the presser 50 and raises it. The heel may now be positioned relatively to the forward end of the gage plate 60 which is adjusted to the line of cut to be made by the knife. As the shoe is raised 75 farther the heel comes in contact with the knife, which, being rapidly vibrated as described, passes easily through the heel with comparatively little effort on the part of the operator until further movement of the shoe 80 is arrested by contact of the shoe with the stop 120. The jack is then lowered and the shoe removed.

Having described my invention, what I claim as new and desire to secure by Letters 85 Patent of the United States is:—

1. In a machine for operating upon boots and shoes, the combination of a knife, and power means for rapidly vibrating the knife substantially about a point located within 90 the knife and adjacent to its edge.

2. In a machine for treating the heels of boots and shoes, the combination of a knife, means for raising the shoe toward the knife, and means for vibrating the knife substantially about a point located in its cutting 95 edge.

3. In a machine for treating the heels of boots and shoes, the combination of a knife, and power means for rapidly vibrating the 100 knife about a movable axis, the locus of which is perpendicular to the plane of the knife.

4. A machine of the class described having, in combination, a knife, a shoe support, 105 means for manually moving the support toward and from the knife and means for oscillating the knife about a substantially stationary point located in the cutting edge of the knife.

5. In a machine of the class described, a machine head, a knife carrier, inclined links supporting the carrier on said head, and means for rocking the carrier on said links.

6. In a machine of the class described, a 115 knife, a carrier therefor, carrier supporting links downwardly and inwardly inclined toward the knife edge, and means for vibrating the carrier on the links.

7. In a machine of the class described, a 120 frame, a knife, a knife carrier, means for supporting the carrier for oscillatory movement comprising links pivoted respectively to the carrier and to the frame, the longitudinal axes of said links being inclined to 125 each other and intersecting when extended near the cutting edge of the knife, and means for vibrating the carrier on the links.

8. A heel breasting machine having, in combination, a vertically movable shoe sup- 130

port, a resiliently depressed tread plate with which the shoe contacts as it is raised by the support and which is raised by the shoe against said resilient means, means on the plate for indicating the position of the cut to be made by the knife, and a knife vibrating substantially at right angles to the plane of the plate against which the shoe is brought by further elevation of the support.

10. A heel breasting machine having, in combination, a vertically movable shoe support, a resiliently depressed tread plate with which the shoe contacts as it is raised by the support and which is raised by the shoe against said resilient means, means on the plate for indicating the position of the cut to be made by the knife, and a knife mounted for vibration about a variable axis the locus of which intersects the plane in which the knife vibrates.

15. A machine of the class described, having, in combination, a knife, a knife carrier, links for supporting the carrier to permit oscillation of the carrier upon said links, and means for varying the relation of the longitudinal axes of the links to each other.

20. A machine of the class described, having, in combination, a knife, a knife carrier, inclined links supporting the carrier for vibration thereon in the plane of the knife, and means for varying the inclination of said links and thereby varying the position of the axis about which the carrier vibrates.

25. A machine of the class described, having, in combination, a knife, a knife carrier, inclined links supporting the carrier for vibration thereon, means for vibrating the carrier, and means for varying equally and oppositely the inclination of the links with respect to the longitudinal axis of the knife to vary the movement of the knife.

30. A machine of the class described, having, in combination, a knife, a work support, means for moving relatively the work support and the knife edge, and power means for giving the knife a rapid vibratory movement of rotation in its own plane.

35. A machine of the class described, having, in combination, a knife carrier, means for vibrating the carrier about a movable point the locus of which lies outside the carrier, a knife on said carrier, means for raising the shoe toward the knife, a resiliently supported tread presser plate for engaging the heel, and means for limiting the action of the knife upon the shoe.

40. A machine of the class described, having, in combination, a knife a part of which is substantially stationary, means for imparting rapid motion to other parts of the knife, a work support adapted to raise the work into operative relation to the knife, yielding means engaging the upper face of the work and movable therewith to hold the

same during the action of the knife, and stop means for limiting the cutting action of the knife.

45. A machine of the class described, having in combination, a knife arranged to vibrate about a substantially stationary point in the plane of the knife, a work support adapted to raise the work into operative relation to the knife, means engaging the work and movable therewith to hold the same during the action of the knife, and stop means for limiting the cutting action thereof.

50. A machine of the class described, having in combination, a knife arranged to vibrate substantially about an axis perpendicular to and passing through the knife, a work support adapted to raise the work into operative relation to the knife, and means for arresting the cutting action of the knife.

55. A machine of the class described, having in combination, a knife, a carrier for the knife, power means for giving rapid vibratory movement to the carrier about a substantially relatively stationary axis, and means for varying the position of the axis relatively to the knife edge.

60. A machine of the class described, having in combination, a knife, a carrier for holding the knife, power means for giving rapid vibratory movement to the knife carrier substantially about an axis perpendicular to the plane of the knife, and means for varying the position of said axis longitudinally of the knife.

65. A machine of the class described, having in combination, a knife having an edge curved in the plane of the knife, and means for so moving the knife about an axis perpendicular to its own plane that a shoe having a shank of greater curvature than the knife will be breasted.

70. A machine of the class described, having in combination, a knife having an edge curved in the plane of the knife, and means for moving the knife in its own plane about a horizontal axis substantially parallel with the longitudinal axis of the shoe so that the limits of its movement lie in a line having a sharply curved central portion flanked by portions of less curvature whereby a shank having a central ridge may be breasted, said shank having a greater curvature than the knife.

75. A heel breasting machine, having in combination, a shoe support, a chisel knife between which there is relative reciprocatory movement in a direction perpendicular to the tread face of the heel, and power means for rapidly oscillating the knife and the shoe relatively about an axis extending lengthwise of the shoe.

80. A heel breasting machine, having in combination a shoe support, a chisel knife, and means for actuating the knife about an axis extending lengthwise of the shoe so

that the heel will be breasted progressively from tread face to heel seat by cuts made on opposite sides of the heel breast alternately.

24. A heel breasting machine, having in combination, a shoe support, a chisel knife, and means for oscillating the knife in the direction of its width about a substantially fixed axis located near the middle of its edge.

Copies of this patent may be obtained for five cents each, by addressing the "Commissioner of Patents, Washington, D. C."

In testimony whereof I have signed my name to this specification in the presence of 10 two subscribing witnesses.

EDWARD ERICKSON.
